UNITED STATES PATENT OFFICE

158,213

BOTTLE

William A. Nester, East St. Louis, Ill., assignor to
 Obear-Nester Glass Company, East St. Louis,
 Ill., a corporation of Missouri

Application January 3, 1949, Serial No. 3

Term of patent 14 years

(Cl. D58—8)

To all whom it may concern:

Be it known that the undersigned, William A. Nester, a citizen of the United States, residing in East St. Louis, Illinois, has invented a new, original, and ornamental Design for Bottle, of which the following is a specification, reference being had to the accompanying drawing, forming a part thereof, in which:

Fig. 1 is a front view of a bottle showing my new design;

Fig. 2 is a side view taken from the right side of Fig. 1;

Fig. 3 is a rear view;

Fig. 4 is a top view; and

Figs. 5, 6 and 7 are sectional views taken on the lines 5—5, 6—6 and 7—7, respectively, of Fig. 1.

I claim:

The ornamental design for a bottle, substantially as shown.

WILLIAM A. NESTER.
